UNITED STATES PATENT OFFICE.

JOHN C. MARTIN, OF TUSCARORA, NEVADA, ASSIGNOR OF ONE-HALF TO
GEORGE T. REDSULL AND WILL. W. ROGERS, BOTH OF SAME PLACE.

MINER'S CANDLESTICK.

SPECIFICATION forming part of Letters Patent No. 275,057, dated April 3, 1883.

Application filed September 1, 1882. (Model.)

To all whom it may concern:

Be it known that I, JOHN C. MARTIN, of Tuscarora, Elko county, Nevada, have invented a new and Improved Miner's Candlestick, of which the following is a full, clear, and exact description.

The object of my invention is to produce a new and improved candlestick combined with other implements used by miners in preparing blasts, which candlestick and implements can be folded very compactly, so that they can be carried in a pocket very conveniently and cannot injure the person.

The invention consists in a spring-frame provided with flanges at the end of one shank and having a knife-blade, a prong, &c., pivoted to the other shank, which flanges hold the same in position either opened or closed.

The invention further consists in a pivoted hook provided at its pivoted end with a jaw, which, with a jaw on the spring-frame, serves to clinch a cap on a fuse.

The invention further consists in a latch for locking the pivoted hook in position either when opened or closed.

The invention also consists in the construction of parts and combination of the same, as will be fully described and set forth herein-after.

Reference is to be had to the accompanying drawings, forming a part of this specification, in which similar letters of reference indicate corresponding parts in all the figures.

Figure 1 is a longitudinal elevation of my improved miner's candlestick, showing the hook raised and the prong projecting from the end of the frame, parts of which are broken out. Fig. 2 is a plan view of the same, showing the end of the spring-frame separated. Fig. 3 is a longitudinal elevation of the candlestick, showing all parts folded within the spring-frame. Fig. 4 is a front end elevation of the same; and Fig. 5 is a plan view of the under side of the candlestick, showing all parts folded within the frame.

A loop-shaped spring-frame, A, is constructed at the open end so that long shanks A' A², which rest against each other and are pressed each by the spring of the frame, will be formed.

To the end of one shank, A', a knife-blade, B, and a sticker or long prong, C, are pivoted on the inner side. The other prong, A², is provided at the end with top and bottom flanges, a, projecting toward the shank A' and adapted to pass over the top and bottom edges of the same and of the pivoted ends of the blade B and sticker C, as shown in Figs. 3 and 5. A spring-loop, D, adapted to receive a candle, projects from the outer surface of the shank A' a short distance from the free end of the same. A hook, E, is pivoted to the inner surface of the prong A² in such a manner that the hook can pass within the enlarged part of the frame A, and beyond the pivot the shank of the hook is provided with a curved prong, having a jaw, F. A fixed jaw, G, corresponding in position with the jaw F, projects from the lower edge of the shank A². A latch, H, is pivoted to the under edge of the shank of the hook E, at or near the middle of the same, in such a manner that it swings laterally—that is, sidewise—on the said hook. The said latch H is provided on its outer end with a hook adapted to catch on a hook-projection, g, on the lower edge of the shank A². The latch H is also provided at its free end with a shoulder, h, adapted to rest on the upper edge of the shank A² when the hook E is raised. The latch H is provided with a lug or projection, I, against which a finger can be rested to move the latch.

The instrument is used as follows: A candle is placed in the loop D. The shanks A' and A² are separated sufficiently to let the blade B and the sticker C drop, and then the blade B is pushed back and the sticker C is swung upward to project from the end of the frame A, and the same is then driven or pushed into a post, &c. The flanges a hold the blade B, and the sticker C is placed either within the frame A or projecting from the same, and prevents them from doubling over. If the holder is to be suspended, the sticker is folded into the frame and the hook E is swung upward and is held in place by the latch H, which is rested against the upper edge of the shank A². The end of the hook E is forced into a log or post. When the hook E is folded in the frame A it is held in place by moving the

latch H sidewise, so that the hook *d* catches on the hook *g*. The jaws F and G are used to clinch a cap on a fuse; and for this purpose a fuse is passed into the cap, which is placed between the jaws, which are then pressed together and force part of the tube of the cap into the fuse. The knife-blade B is used to cut fuses, and for other suitable purposes.

Having thus described my invention, I claim as new and desire to secure by Letters Patent—

1. The combination, with the spring-frame A, having flanges *a a* at the end of one shank, of the blade and prongs pivoted to the opposite shank, substantially as herein shown and described, and for the purpose set forth.

2. The combination, with the spring-frame A, provided with a candle-holding loop, D, and having flanges *a* at the end of the opposite shank, of the knife-blade B and the sticker C, pivoted to the opposite shank, substantially as herein shown and described, and for the purpose set forth.

3. The combination, with a spring-frame to which a knife-blade and a prong are pivoted, of a hook pivoted to one shank and a latch

pivoted to said hook for holding it in the desired position, substantially as herein shown and described, and for the purpose set forth.

4. The combination, with the spring-frame A, provided with a hook-projection, *g*, of the pivoted hook E and the latch H, pivoted to the hook E, and provided at its end with a hook, *d*, substantially as herein shown and described, and for the purpose set forth.

5. The combination, with the spring-frame A, provided with a hook-projection, *g*, of the latch H, pivoted to the hook E, and provided at its end with a hook, *g'*, and a shoulder, *h*, substantially as herein shown and described, and for the purpose set forth.

6. The combination, with the spring-frame A, provided with a jaw, G, projecting from its edge, of the pivoted hook E, provided with a jaw, F, substantially as herein shown and described, and for the purpose set forth.

JOHN COLUMBUS MARTIN.
